CLAIM

The ornamental design for a combined confectionery tray, advertising holder and donation box, as shown and described.

DESCRIPTION

FIG. 1 is a perspective view of a combined confectionery tray, advertising holder and donation box showing my new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a rear elevational view thereof;

FIG. 7 is a front elevational view thereof;

FIG. 8 is a perspective view of a combined confectionery tray, advertising holder and donation box showing a modification of my new design;

FIG. 9 is a top plan view thereof;

FIG. 10 is a left side elevational view thereof;

FIG. 11 is a bottom plan view thereof;

FIG. 12 is a right side elevational view thereof;

FIG. 13 is a rear elevational view thereof; and

FIG. 14 is a front elevational view thereof.
